Fig. 2

Fig. 3

FIG. 1 is an elevational view of a vehicle side brush mount showing my new design as it appears with the brush arms extended in line from the central pod.

FIG. 2 is a view thereof looking in the opposite direction.

FIG. 3 is a top plan view thereof.

FIG. 4 is an elevational view thereof as the design appears looking from left to right in FIGS. 2 and 3.

FIG. 5 is an elevational view thereof as seen looking from right to left in FIGS. 2 and 3.

Dominant features of my design reside in portions shown in full lines.

I claim:

The ornamental design for a vehicle side brush mount, substantially as shown and described.
